(57) **CLAIM**

The ornamental design for a mobile phone, as shown and described.

DESCRIPTION

FIG. 1 is a front view of a first embodiment of the new design, showing a mobile phone;

FIG. 2 is a back view of the first embodiment of a mobile phone;

FIG. 3 is a left view of the first embodiment of a mobile phone;

FIG. 4 is a right view of the first embodiment of a mobile phone;

FIG. 5 is a top view of the first embodiment of a mobile phone;

FIG. 6 is a bottom view of the first embodiment of a mobile phone;

FIG. 7 is a perspective view of the first embodiment of a mobile phone;

FIG. 8 is another perspective view of the first embodiment of a mobile phone;

FIG. 9 is a front view of the first embodiment of a mobile phone, shown in a folded state;

FIG. 10 is a back view of the first embodiment of a mobile phone, shown in a folded state;

FIG. 11 is a left view of the first embodiment of a mobile phone, shown in a folded state;

FIG. 12 is a right view of the first embodiment of a mobile phone, shown in a folded state;

FIG. 13 is a top view of the first embodiment of a mobile phone, shown in a folded state;

FIG. 14 is a bottom view of the first embodiment of a mobile phone, shown in a folded state;

FIG. 15 is a perspective view of the first embodiment of a mobile phone, shown in a folded state;

FIG. 16 is another perspective view of the first embodiment of a mobile phone, shown in a folded state;

(Continued)

FIG. 17 is a perspective view showing a usage state of the mobile phone of the first embodiment, in which the screen shows a gray tone;

FIG. 18 is another perspective view showing a usage state of the mobile phone of the first embodiment, in which the screen shows a gray tone;

FIG. 19 is another perspective view showing a usage state of the mobile phone of the first embodiment in a folded state, in which the screen shows a gray tone;

FIG. 20 is a front view of a second embodiment of the new design, showing a mobile phone;

FIG. 21 is a back view of the second embodiment of a mobile phone;

FIG. 22 is a left view of the second embodiment of a mobile phone;

FIG. 23 is a right view of the second embodiment of a mobile phone;

FIG. 24 is a top view of the second embodiment of a mobile phone;

FIG. 25 is a bottom view of the second embodiment of a mobile phone;

FIG. 26 is a perspective view of the second embodiment of a mobile phone;

FIG. 27 is another perspective view of the second embodiment of a mobile phone;

FIG. 28 is a front view of the second embodiment of a mobile phone, shown in a folded state;

FIG. 29 is a back view of the second embodiment of a mobile phone, shown in a folded state;

FIG. 30 is a left view of the second embodiment of a mobile phone, shown in a folded state;

FIG. 31 is a right view of the second embodiment of a mobile phone, shown in a folded state;

FIG. 32 is a top view of the second embodiment of a mobile phone, shown in a folded state;

FIG. 33 is a bottom view of the second embodiment of a mobile phone, shown in a folded state;

FIG. 34 is a perspective view of the second embodiment of a mobile phone, shown in a folded state;

FIG. 35 is another perspective view of the second embodiment of a mobile phone, shown in a folded state;

FIG. 36 is a perspective view showing a usage state of the mobile phone of the second embodiment in a folded state, in which the screen shows a gray tone;

FIG. 37 is another perspective view showing a usage state of the mobile phone of the second embodiment in a folded state, in which the screen shows a gray tone; and,

FIG. 38 is another perspective view showing a usage state of the mobile phone of the second embodiment in a folded state, in which the screen shows a gray tone.
